UNITED STATES PATENT OFFICE.

GEORGE H. RICHARDS, OF SOMERVILLE, MASSACHUSETTS.

DESIGN FOR A BOX.

SPECIFICATION forming part of Design No. 28,641, dated May 17, 1898.

Application filed July 27, 1897. Serial No. 646,151. Term of patent 14 years.

To all whom it may concern:

Be it known that I, GEORGE H. RICHARDS, of Somerville, in the county of Middlesex and State of Massachusetts, have invented and 5 produced a new and original Design for a Box, of which the following, taken in connection with the accompanying drawing, is a specification.

My design is embodied in a box in the form 10 of a hollow triangular prism closed at both ends by plane triangular faces parallel with each other.

The triangular ends of the box have a substantially triangular central panel of a color 15 contrasting sharply with that of the broad surrounding margin. One angle of this triangular panel is cut off by a transverse line. The rectangular panels forming the sides have a narrow margin of a color contrasting with 20 that of the said panels. One of these rectangular panels has a broad diagonal band of a contrasting color dividing it into two right-angled triangles.

I am aware of and I disclaim the triangular designs for lanterns set forth in the design 25 patents to Clough and Fountain, dated July 19, 1864, No. D 1,971, and to Alexander, dated February 4, 1868, No. D 2,905, such lanterns showing end openings for ventilation, external handles, and projecting tops or bottoms 30 and having no ornamentation conforming to mine. The appearance is consequently quite unlike my design.

I claim as my invention—

The design for a box substantially as shown 35 and described.

In testimony whereof I have signed my name to this specification in the presence of two subscribing witnesses.

GEORGE H. RICHARDS.
